FIRE EXTINGUISHER OR SIMILAR ARTICLE

Oscar Doster, 49 Brixham Terrace, Toronto,
Ontario, Canada

Filed July 2, 1962, Ser. No. 70,772

Term of patent 14 years

(Cl. D16—2)

FIG. 1 is a side elevation view of a fire extinguisher or similar article embodying my new design;

FIG. 2 is a top plan view thereof; and

FIG. 3 is a bottom plan view thereof.

The side not shown in FIGURE 1 is a mirror image of the side shown.

I claim:

The ornamental design for a fire extinguisher or similar article, as shown and described.
